UNITED STATES PATENT OFFICE.

HENRY W. COVERT, OF WATERFORD, NEW YORK.

CONVERTIBLE CAR.

SPECIFICATION forming part of Letters Patent No. 736,941, dated August 25, 1903.

Application filed June 19, 1903. Serial No. 162,202. (No model.)

To all whom it may concern:

Be it known that I, HENRY W. COVERT, a citizen of the United States, residing at Waterford, county of Saratoga, and State of New York, have invented certain new and useful Improvements in Convertible Cars, of which the following is a specification.

The invention relates to such improvements and consists of the novel construction and combination of parts hereinafter described and subsequently claimed.

Reference may be had to the accompanying drawings and the reference characters marked thereon, which form a part of this specification.

Similar characters refer to similar parts in the several figures.

Figure 1 of the drawings is a view in side elevation, partly broken away, of my improved convertible car. Fig. 2 is a vertical cross-section of the same, taken on the broken line 2 2 in Fig. 1, with the side doors closed and the panels lowered on one side and the panels raised on the other side. Fig. 3 is a vertical cross-section of one of the seats, taken on the broken line 3 3 in Fig. 2. Fig. 4 is a horizontal cross-section of the car, taken on the broken line 4 4 in Fig. 2. Fig. 5 is a view in perspective, on an enlarged scale, showing a portion of the floor, door, and door-locking slide-bar, illustrating the manner in which the doors are locked. Fig. 6 is a view, on an enlarged scale, of the lower end of one of the pockets adapted to receive the panels when raised. Fig. 7 is a vertical cross-section of the same, taken on the broken line 7 7 in Fig. 6. Fig. 8 is a view, on an enlarged scale, in vertical cross-section, taken on the broken line 8 8 in Fig. 1, illustrating the joint formed by the meeting edges of the two sashes. Fig. 9 is a view, on an enlarged scale, showing in side elevation a portion of one of the vertical posts, a portion of the sash located in the slideway in said post, and brake mechanism on said sash. Fig. 10 is a vertical cross-section of the sash, taken on the broken line 10 10 in Fig. 9. Fig. 11 is a vertical cross-section of the sash and post, taken on the broken line 11 11 in Fig. 9. Fig. 12 is a view similar to Fig. 4, showing a different arrangement of seats.

My invention relates to the class of cars

provided with side openings formed between vertical side posts or ribs adapted to support movable members for closing said openings at certain times, as in cold or inclement weather, means being provided for disposing of said members to leave open the spaces between the side posts when an open car is desired.

The principal objects of this invention are to facilitate the disposal, when an open car is desired, of the movable side members, and in this connection to avoid heavily weighting the overhead portion of the car, and to provide seats the capacity of which can be varied as occasion requires.

Other objects will appear in connection with the following description.

In carrying out my invention in its preferred form I employ for closing the lower portions of the side openings horizontally-swinging doors and for closing the upper portions thereof vertically-sliding panels.

Referring to the drawings, 1 represents the floor, and 2 the roof, of the car, which are connected together at intervals by the vertical side posts or ribs 3 in the usual manner, forming between said posts side openings which can be used for the entrance and exit of passengers. From the lintel 4 downwardly about half-way to the floor 2 these side openings extend from post to post and are adapted to be closed by glazed panels 5, fitting and movable along grooves 6 in the posts, in the manner shown and described in United States Letters Patent No. 698,259, dated April 22, 1902, granted to me for improvements in convertible cars. As set forth in said patent, the panels 5, of which there are preferably two for each side opening in the present car, can be moved upwardly along the slideway-grooves and deflected into the pocket 7, subjacent to the car-roof.

Below the space closed by the sliding panels the car-body is provided with side wall-sections 8, built around the respective posts, alternating with side openings of equal width therebetween, adapted to be closed, respectively, by the doors 9, each hinged along one of its vertical edges to one of said side wall-sections and adapted to swing horizontally across the neighboring opening to close the same or outwardly against the side wall-sec-

- tion to which it is hinged when it is desired to leave said opening unobstructed for the use of passengers. Each of said doors is provided with a pair of locking-plates 10, de-
 5 pending from its lower end on opposite sides, adapted to be engaged, one when the door is open and the other when the door is closed, by hooks 12 on the locking-bar 13, which is mounted upon the outer side of the sill of the
 10 car by means of bolts 14, inserted through elongated slots 15 in the bar, whereby said bar can be reciprocated longitudinally to cause said hooks to interlock with the respective locking-plates to lock the doors in either the open or closed position. Such a locking-bar 13 is provided on each side of the car, adapted to simultaneously lock or simultaneously unlock all the doors on that side. Reciprocating sliding movements can be im-
 15 parted to the locking-bar by means of the hand-lever 16, fulcrumed upon the outside of the car-body at 17 near one end of the car and connected by link 11 with the locking-bar.
 20 25 The doors are preferably connected with the respective side wall members by hook-and-eye hinges 18, the pins or hooks thereof being of sufficient length to permit any door to be lifted on its hinges sufficiently to raise
 30 the locking-plate 10 above and free from the hook 12 on the locking-bar, whereby the locked doors can be individually unlocked, operated, and relocked.
 35 Any known form of laterally-movable door may be employed for closing the lower portion of the side opening of the car, and the doors may be locked in any known manner, and any known form of vertically-movable panel may be employed to close the upper
 40 portion of such side opening.
 45 The combination of laterally-movable doors for the lower portions of the side openings with vertically-movable panels for the upper portions thereof permits the extension of the side openings each from the sill to the lintel or shoulder of the car without overweighting the upper portion of the car, as in cases where such openings are wholly closed by vertically-movable panels.
 50 55 In using the preferred form of panel shown I preferably provide in the bottom of the pocket 7 a separate recess or socket 19, adapted to receive the lower end of the panel which last enters the pocket, which is the lower panel used to close the side opening. The sockets 19 do not extend to the full width of the pocket, but are formed to leave along the end wall of the pocket an outwardly and downwardly inclined surface 20, as shown in
 60 65 said patent, adapted to receive and support the lower edge of upper panel. The corner portions of the lower panel are cut away to adapt them to enter said sockets 19, as shown at 21, whereby the lower panel when deflected into the pocket and seated in the sockets 19 is not only prevented from being displaced by the jar or vibration of the car, but also

serves to prevent displacement of the other panel.

The car-body is provided with end openings 70 or doorways 22, closed by sliding doors 23, arranged diagonally opposite each other, each adjacent to a side wall of the car, whereby passengers may enter and leave the car when the side openings are closed. In this connection I have shown a novel form of seat construction which permits the formation of an unobstructed aisle along either side of the car in line with one of said end openings. This seat construction comprises a row of stationary seats 24, each of less width than the interior of the car, arranged along the longitudinal middle of the car, and in telescopic relation with each of said stationary seats a pair of extension-seats 25, arranged at opposite ends thereof. The extension-seats have their inner ends adapted to slide in ways 26, formed beneath the stationary seat, while their outer ends are severally supported by a standard 27, having a roller-foot 28, adapted 90 to rest upon the floor.

The relative dimensions of the stationary and extension seats are such that only one of the extension-seats can be fully contained within the stationary seat at a time, and the 95 parts are so arranged that when one of the extension-seats is forced into one end of a stationary seat it automatically engages and forces out from the other end of said stationary seat the other extension-seat, as shown 100 in the broken-away portion of Fig. 2. It is possible with this construction to at all times leave an unobstructed aisle between the stationary seats and one or the other of the side walls of the car, which aisle is in line with an 105 end opening 22 and can be used by passengers entering or leaving the car by said end opening. The seats can be made reversible by having the backs 30 of the stationary seats hinged at 31 upon stationary brackets 32 and 110 the outer end of the back 33 of each extension-seat in like manner hinged at 34 upon the bracket 35, formed integral with the roller-supported standard 27, the inner end of said back of the extension-seat being adapted to 115 telescope within the back of the stationary seat. Both of the extension-seats can be extended across the side aisles when increased seating capacity is desired. The stationary seats 36 may be provided in the diagonally-120 opposite corners of the car not occupied by the doorways 22.

The roller-curtain 37 is adapted to travel in the grooves 38 in the posts on opposite sides of a side opening to temporarily close said 125 opening in the usual manner.

When the car is used as a closed car, ventilation can be provided by opening the ventilator 39 in each end of the car, the openings so formed communicating with the space beneath the hood 40 of the vestibule 41. The vertical sides of said hood are provided with openings covered by netting 42.

As a means for retarding the descent of the

panels in their slideway-grooves I provide each panel with a brake comprising a roller 45, adapted to ride upon the downwardly and inwardly inclined surface 46 of the rubber block 47, contained within the housing 48, secured in an opening in the vertical edge of the sash in such a manner that said roller projects beyond the inner surface of the sash and is adapted to engage the inner side wall of the 10 groove in which the sash slides, and as the roller is forced by the descending movement of the sash and its engagement with said inner side wall 49 of the groove to ride up the incline 46 the outer side of the sash will be 15 forced tightly against the outer side wall 50 of said groove to frictionally retard the descent of the sash. A cap 51 extends across the open end of the housing 48 just outside the line of the grooved post and serves to retain the roller within the housing when the sash is located in a raised position in a pocket in the upper part of the car.

When it is desired to use the car as a closed car for a considerable period, auxiliary panels 25 53 may be detachably secured in the spaces between the side wall-sections 8, as by the buttons 54.

In Fig. 12 of the drawings I have shown my improved seat construction adapted for use 30 to temporarily block or obstruct lower portions of the side openings of the car. For this purpose I dispose the seats in line with the respective side openings instead of in line with the wall-sections which alternate with 35 such openings, the arrangement being such that when an extension-seat neighboring one of said side openings is extended it serves to block or obstruct said opening, preventing the use of said side opening for the entrance 40 and exit of passengers. This arrangement of seats makes it unnecessary when an open car is desired to close the doors on either side of the car regardless of the direction in which the car is moving.

45 What I claim as new, and desire to secure by Letters Patent, is—

1. In a convertible car, the combination with the car-body provided with side openings; of horizontally-movable doors for closing the lower portions of the respective side openings; and vertically-movable panels for closing the upper portions of said side openings above said doors.

2. In a convertible car, the combination 55 with the car-body provided with side openings, and having grooved side members on opposite sides of the respective side openings; of horizontally-movable doors for closing the lower portions of the respective side openings; and panels vertically movable in said grooves for closing the upper portions of said openings above said doors.

3. In a convertible car, the combination 65 with the car-body provided with side openings, and having side members on opposite sides of said side openings; of doors severally hinged to the lower portions of the respective

side members to swing upon a vertical axis; and panels adapted to slide in vertical grooves in the upper portions of said side members. 70

4. In a convertible car, the combination with the car-body provided with side openings, and having side members on opposite sides of the respective side openings; of doors severally hinged to the respective side members 75 adapted to swing upon a vertical axis; locking mechanism adapted to engage the respective doors in their open or closed position; and means for simultaneously operating the locking mechanism of a series of said doors on the same side of the car, substantially as described.

5. In a convertible car, the combination with the car-body provided with side openings, and having side members on opposite 85 sides of the respective side openings; of doors severally hinged to the respective side members adapted to swing upon a vertical axis; locking-plates on the lower ends of the respective doors; a locking-bar extending longitudinally of the side of the car adjacent to the lower ends of the several doors on that side; means for communicating reciprocating slide movements to said bar from one end of the car; and hooks on said bar adapted to engage the locking-plates on the lower ends of 90 said doors respectively.

6. In a convertible car, the combination with the car-body provided with side openings, and having side members on opposite 100 sides of the respective side openings; of swing-doors; a locking-bar; locking members adapted to be simultaneously operated by said locking-bar engageable with depending portions of the respective doors on one side of the car 105 whereby all the doors of said series can be simultaneously locked or simultaneously unlocked; means for operating said locking-bar; and hook-and-eye hinge connections between said doors and the respective side members whereby an individual door can be lifted 110 on its hinges to release it from the control of the locking member, substantially as described.

7. In a car, the combination with the car-body having an aisle along each side thereof; of a transverse seat fixed between said aisles; and a pair of movable seats in telescopic connection with the opposite ends of said fixed seat, extensible across said respective aisles. 115 120

8. In a car, the combination with the car-body having an aisle along each side thereof; of a transverse seat fixed between said aisles; and a pair of movable seats in telescopic connection with the opposite ends of the fixed 125 seat, and of a combined length greater than that of the fixed seat, whereby a telescoping movement of either movable seat causes the same to engage and extend the other movable seat.

9. In a car, the combination with the car-body having a side aisle; of a transverse seat fixed at one side of said aisle; a movable seat extensible across said aisle having one end in 130

telescopic connection with said fixed seat; and a movable standard fixed to the other end of the movable seat.

10. In a convertible car, the combination 5 with the car-body provided with side openings; and end openings diagonally opposite each other, and having an aisle along each side in line with the respective end openings; of movable members for closing the respective side and end openings; transverse seats fixed between said aisles; and a pair of movable seats in telescopic connection with the opposite ends of each of said fixed seats extensible across said respective aisles.
- 15 11. In a convertible car, the combination with the car-body having members adjacent to a side opening each provided with a slide-way-groove and at the upper end with a laterally-extended pocket communicating with 20 said groove, having an outwardly and downwardly inclined bottom surface, the bottom being partly cut away to form near said groove a recess to receive the lower edge of a panel, said inclined surface extending continuously 25 from said groove back of said recess to the outer side of the pocket; of a pair of panels movable along said groove capable of deflection into said pocket, the upper panel having its lower end of a width to overlap said inclined bottom surface and being adapted to 30

be guided thereby past said recess, and the lower panel being cut away at its lower corner to adapt it to enter said recess, substantially as described.

12. In a car, the combination with the car- 35 body having a side wall provided with an opening for the exit and entrance of passengers, and having an aisle extending along said side wall; of a transverse seat fixed in line with said opening on the opposite side of said aisle; 40 and a movable seat in telescopic connection with said fixed seat extensible across said aisle to obstruct said opening.

13. In a car, the combination with the car- body having in its opposite sides openings in 45 line with each other for the exit and entrance of passengers, and an aisle along each of said sides; of transverse seats fixed between said aisles in line with the respective side openings; and a pair of movable seats in telescopic 50 connection with the opposite ends of each fixed seat extensible across the respective aisles to obstruct the respective openings in line with said fixed seat.

In testimony whereof I have hereunto set 55 my hand this 17th day of June, 1903.

HENRY W. COVERT.
